UNITED STATES PATENT OFFICE.

JOHN HAGEDORN, OF SALEM, MISSOURI.

SPRING-CULTIVATOR.

No. 906,414.

Specification of Letters Patent.

Patented Dec. 8, 1908.

Application filed September 4, 1907. Serial No. 391,371.

To all whom it may concern:

Be it known that I, JOHN HAGEDORN, a citizen of the United States, residing at Salem, in the county of Dent and State of Missouri, have invented a new and useful Spring-Cultivator, of which the following is a specification.

The invention relates to improvements in cultivators.

10 The object of the present invention is to improve the construction of cultivators, and to provide a simple and comparatively inexpensive one of great strength and durability, designed particularly for use on rocky and 15 stumpy ground, and having resilient cultivating devices, which will not be broken should they come in contact with a rock or stump.

20 A further object of the invention is to provide a cultivator of this character, capable of lateral movement and adapted to be easily shifted from one side to the other for dodging corn, or a stump, and also for moving it upward when cultivating a hillside, whereby 25 the cultivator is prevented from slipping down the same.

It is also the object of the invention to 30 provide a cultivator, which, should any of its parts become broken, may be readily repaired by an ordinary blacksmith, so as to avoid the inconvenience and expense of shipping the cultivator, or any portion thereof back to the factory for repair.

With these and other objects in view, the 35 invention consists in the construction and novel combination of parts hereinafter fully described, illustrated in the accompanying drawing, and pointed out in the claims hereto appended; it being understood that various 40 changes in the form, proportion, size and minor details of construction, within the scope of the claims, may be resorted to without departing from the spirit or sacrificing any of the advantages of the invention.

45 In the drawings:—Figure 1 is a side elevation of a cultivator, constructed in accordance with this invention. Fig. 2 is a central longitudinal sectional view of the same. Fig. 3 is a plan view of the cultivator. Fig. 4 is a rear elevation of the same. Fig. 5 is a 50 detail sectional view, illustrating the manner of mounting the spring cultivating devices. Fig. 6 is an enlarged detail perspective view of one side of the main frame, illustrating the 55 construction and arrangement of the easter wheel for supporting the same. Fig. 7 is a

side elevation of the cultivator, the transverse supporting bar being interposed between the easter wheel frames and the main frame to interlock the same and to support 60 the cultivating devices above the ground. Fig. 8 is a rear elevation, partly in section.

Like numerals of reference designate corresponding parts in all the figures of the drawings.

65 The main frame of the machine, which is preferably constructed of a combination of wood and metal, is provided with front and rear continuous top transverse bars 1 and 2 and front and rear bottom transverse bars 3 and 4, arranged in pairs and located at opposite sides of the center of the cultivator, and connected with the top transverse bars by means of front and rear arches 5 and 6. The top transverse bars, which extend entirely 70 across the cultivator, are connected at their terminals by longitudinal end bars 7, and the bottom transverse bars are also connected at their outer ends by longitudinal end bars 8. The transverse bars and the said end bars are 75 preferably constructed of wood, such as well seasoned oak, or other suitable material, and the top transverse bars are connected by centrally arranged diagonal braces 9 and metallic longitudinal bars 10, located adjacent to the 80 wooden end bars 7, as clearly illustrated in Fig. 3 of the drawings. The diagonally arranged braces, which are crossed beneath the rear portion of a centrally arranged draft beam or tongue 11, are secured at their terminals to the lower faces of the top transverse bars, and they prevent the top of the main 85 frame from sagging.

90 The front and rear arches, which are constructed of metal, have upwardly and inwardly inclined sides and side connecting top portions, which are secured to the lower faces of the top transverse bars by the bolts 12 and 13, or other suitable fastening devices, which also secure the rear portion of the draft beam 95 100 or tongue to the top transverse bars. The draft beam or tongue is recessed at its lower face to receive the top transverse bars, and it assists in bracing the top of the main frame. The arches are provided at the lower ends of 105 their sides with outwardly extending transverse portions or arms 14 and 15, arranged at the upper faces of the bottom transverse bars and reinforcing the same, as clearly illustrated in Fig. 7 of the drawings. The top 110 and bottom transverse bars are connected at the sides of the cultivator by means of front

and rear vertical bars or members 16 and 17, having their upper and lower terminals bent at right angles and secured to the top and bottom transverse bars. The bottom transverse bars are connected adjacent to the end bar 8 by metallic braces 18, which correspond in arrangement to the upper metallic bars or braces 10. The metallic portions of the main frame are designed to be constructed of malleable metal, or other suitable material and they may be varied in size to provide a frame of the desired strength. Also they are adapted to be readily replaced by an ordinary blacksmith, should any of the parts become broken.

The cultivator is provided at each side with a plurality of spring cultivating devices, which are adapted to yield to prevent injury to them should they strike a stump or rock. In the accompanying drawings, the cultivator is equipped with two of these cultivating devices at each side of the main frame, but three or more may be employed, as will be readily understood. The inner cultivating devices 19 carry shovels 20, which are arranged in advance of the shovels 21 of the outer cultivating devices 22, but the cultivating devices may be reversed as they are detachable and adjustable, as hereinafter more fully explained. Each spring cultivating device consists of a main longitudinal spring 23 and a rear bracing spring 24, as clearly illustrated in Fig. 6 of the drawings. The main longitudinal spring has its front portion 25 curved upwardly, and its rear portion 26 is curved downwardly, the intermediate connecting portion 27 being approximately straight. The front end of the longitudinal spring 23 is bent at an angle, and is secured to the lower face of the front bottom transverse bar 3 by a bolt 28, but the front end of the spring 23 is adapted to be arranged at either the upper or lower face of the bar 3 to adjust the rear end of the cultivating device. The rear spring 24 is provided with a substantially semi-circular front portion 29, extending upwardly from the main longitudinal spring at a point near the center thereof and secured at its upper end to the lower face of the rear transverse bottom bar 4 by a bolt 31. The rear spring is also provided with a straight intermediate portion 32 and a downwardly curved rear portion 33, which fits the straight rear portion 27 and the downwardly curved portion 26 of the main longitudinal spring 23 to reinforce the same and to provide a resilient cultivating device of great strength and durability. The resiliency of the cultivating device, however, may be increased by omitting the straight portion 32 and the downwardly curved rear portion 33 of the rear spring. The rear spring 24 forms a yieldable connection between the main longitudinal spring and the rear transverse bottom bar;

and it permits the front end of the main longitudinal spring to be arranged on either the upper or lower face of the front transverse bottom bar 3. By transferring the front end of the main longitudinal spring 23 from the bottom to the top of the bar 3, the rear end of the cultivating device is thrown downward in the direction of the ground, and a reverse movement of the front end of the main longitudinal portion 23 operates to raise the rear end of the cultivating device. The cultivating devices may be equipped with any preferred form of soil-engaging device, and the blades or shovels may be arranged to throw the soil in either direction. The bottom transverse bars and the laterally extending arms or portions of the front and rear arches are provided at intervals with perforations 34 and 35, to permit the cultivating devices to be adjusted toward and from each other, and to be arranged either in parallelism with the tongue or at an angle to the same. When the cultivating devices are arranged in parallelism with the beam, as illustrated in Fig. 3 of the drawings, corn can be cultivated without ridging the ground, which will be left level. The blades or shovels are detachably secured to the rear ends of the cultivating devices, and are adapted to be readily removed to sharpen them or for any other purpose.

The sets of cultivating devices are connected by transverse and diagonal braces 36 and 37, secured to the cultivating devices at the intermediate straight portions of the springs by bolts, or other suitable fastening devices and provided with a plurality of perforations to permit the lateral adjustment of the cultivating devices. The diagonal braces 37 extend rearwardly and laterally from the inner ends of the transverse braces 36 to the outer cultivating devices, and their rear ends are secured to the same at the rear terminals of the straight portions of the springs thereof.

The cultivator is provided at opposite sides of the center with fender blades 38, arranged in spaced relation, as clearly illustrated in Figs. 3 and 4 of the drawings, and adapted to prevent the cultivator from throwing the soil upon and injuring the young plants. The fenders are provided at their front ends with arms 29, having laterally extending top portions 40, which are adjustably secured to the front transverse bottom bars 3, suitable perforations being provided for securing the front ends of the longitudinal springs to the said bars 3. This construction permits the fender blades to be arranged the desired distance apart.

The main frame of the cultivator is supported by caster wheels 41, mounted on suitable axles 42 of approximately triangular frames 43, consisting of a longitudinal top bar 44, depending rear arms 45 and inclined

braces 46, extending upwardly from the lower ends of the rear arms 45 to the front end of the top bar 44. The front end of the top bar 44 is provided with a perforation through which passes a vertically adjustable rod 47. The vertically adjustable rod 47, which is mounted in openings of the top and bottom end bars of the main frame of the cultivator, forms a pivot for the triangular frame of the 10 caster wheels. The triangular frame is shiftable transversely of the main frame, and it is provided at its back with an upwardly extending arm or post 48, having its upper end bifurcated and receiving an anti-friction 15 wheel 49. The anti-friction wheel is mounted on a suitable axle or spindle 50, and it engages an arcuate track or guide 51, secured to the bottom end bar 8 of the main frame and extending from opposite sides thereof. 20 The anti-friction wheel 49 is adapted to run on the curved track when the triangular frame is shifted in either direction, and it constitutes a fulcrum or bearing for the main frame to enable the latter to be tilted 25 backwardly or forwardly, and it sustains the weight of the cultivator and releases the necks of the draft animals. The terminals of the curved tracks or guides are bent downwardly to form depending stops 51^a, which 30 are arranged in the path of the anti-friction wheels 50 to limit the relative lateral movement of the caster wheels and to prevent the anti-friction device from leaving the tracks or guides. These curved tracks or guides 35 may be of any desired length, and they may be braced at the terminals by inclined rods or bars, extending upwardly from the guides or tracks to the main frame, or they may be strengthened or reinforced in any other preferred manner.

The lower end of the rod 47 passes through the front end of the top bar or member of the triangular frame, and it receives an eye 52 of the lower end of a rod 53, which connects 45 the front of the triangular frame with an adjusting lever 54. The adjusting lever 54, which extends longitudinally of the cultivator, is fulcrumed at an intermediate point on a bolt 55, which pierces the lever and the 50 front vertical bar or member 16. The rear vertical bar or member is equipped with a suitable ratchet 56, which is engaged by a pawl or dog 57 of the adjusting lever, whereby the latter is secured in its adjustment. A 55 coiled spring 58, which is disposed on the lower portion of the rod 47, is interposed between the front of the triangular frame and the lower face of the bottom end bar 8 to facilitate the adjustment of the cultivator. 60 By raising and lowering the rear end of the adjusting lever, the main frame of the cultivator is tilted backwardly or forwardly on the anti-friction device of the caster wheel frame. This will throw the shovels, or other 65 soil-engaging devices into or out of the

ground, and the adjustment may be effected while the cultivator is in operation and without stopping and resetting the cultivating devices. The rear end of the adjusting lever is shaped into a suitable handle 58^a, and the 70 pawl or dog 57 is also provided with an operating arm or handle 59, arranged adjacent to the grip or handle of the adjusting lever. The front portion of the adjusting lever is provided with a slot 60, through which the 75 vertically movable rod 47 passes. The caster wheel enables the cultivator to be shifted laterally for dodging corn or stumps, and also for moving it upwardly while cultivating on a hillside, whereby the cultivator is prevented 80 from slipping down the hill.

The cultivator is provided with a pair of adjustable handles 61, mounted on and extending across the space between the top transverse bars 1 and 2. The front ends of 85 the handles are secured to the front transverse bar 1 by means of bolts, or other suitable fastening devices, and the intermediate portions of the handles are adjustably connected with the rear transverse bar 2 by 90 means of angle plates or brackets 62, secured to the upper face of the said bar 2 and having upwardly extending arms provided with a plurality of perforations 63 for the reception of bolts 64, or other suitable fastening 95 devices. By this construction the handles may be raised or lowered to arrange them to suit either a boy or a man. By pressing down on the handles the cultivator may be tilted on the caster wheels to force the cultivating 100 devices into the ground.

The draft animals are hitched to swingletrees 65, which are secured to the lower ends of the approximately vertical levers 66, connected at their upper ends to and depending 105 from an equalizing bar or member 67. The depending levers 66 are connected at an intermediate point with the front vertical bars or members 16 of the main frame by links 68. The equalizing bar or member is pivoted to 110 the lower face of the draft beam or tongue by a bolt 69, and it is supported by a transverse bar 70, connected with the top of the main frame by a short central brace 71 and with the bottom of the main frame by side braces 115 72. The side braces 72, which are disposed longitudinally of the cultivator, extend across the space between the front and rear bottom transverse bars and are suitably secured to the same to brace the depending 120 side portions of the main frame. The front portions of the braces 72 extend upwardly and are secured to the terminals of the supporting bar 70 at the lower face thereof. The equalizing device enables the draft animals, 125 when drawing the cultivator, to move backwardly and forwardly with relation to each other without twisting the cultivator.

When it is desired to transfer the cultivator from one field or place to another, the 130

cultivating devices are elevated above the ground and the caster wheels are held against lateral movement relative to the main frame. This is effected by means of a transversely disposed supporting bar or bolster 73, designed to be constructed of any suitable material and adapted to be interposed between the top of the caster wheel frames and the bottom of the main frame. The transverse bar or bolster 73 is provided at its ends with upwardly and downwardly projecting arms or portions 74 and 75, and they are fitted against the upwardly extending posts or arms 48 of the caster wheel frames. The upwardly extending arms or portions 74 of the transverse bar or bolster 73 fit against the lower faces of the end bar 8 of the main frame, and they are provided at the outer edges of the latter with upwardly projecting lugs 76. The upwardly extending arms are also provided with projecting studs or pins 77, which fit in perforations 78 of the lower end bar 8, whereby the transverse bar or bolster 73 is detachably interlocked with the main frame. The lower or downwardly extending arms or portions 75 are provided with recesses 79, forming forks or portions, which straddle the longitudinal top bar of the caster wheel frames, whereby the latter are interlocked with the supporting bar or bolster 73. The supporting bar or bolster is adapted to hold the cultivating devices above the ground, as clearly illustrated in Figs. 8 and 9 of the drawings, and the caster wheel frames are rigidly connected with the main frame. The supporting bar or bolster is detachably secured to the upwardly extending arms or posts 48 of the caster wheel frames by means of hooks 80, secured to the bar or bolster 73 and engaging lugs or projections 81, located at the outer side faces of the posts or arms 48, but any other preferred fastening means may be employed for detachably securing the bar or bolster 73 in its interlocked relation with the main frame and the caster wheel frames.

The cultivator may be equipped with a seat for the accommodation of the driver, and instead of employing the blades 21, other forms of cultivating devices may be used. Also the machine may be equipped with a central cultivating device for use when the fenders are not employed.

Having thus fully described my invention, what I claim as new and desire to secure by Letters Patent, is:—

1. In a cultivator, the combination of a main frame embodying a continuous transversely disposed horizontal top portion extending entirely across the cultivator, spaced bottom portions, and front and rear arches connecting the top and bottom portions of the frame, and cultivating devices connected with the spaced bottom portions of the frame.

2. In a cultivator, the combination of a

main frame embodying a continuous transverse top portion, spaced bottom portions, front and rear arches connecting the inner ends of the bottom portions of the frame with the top portion of the same, and front and rear vertical bars connecting the outer ends of the bottom portions of the frame with the ends of the top portions of the same, and cultivating devices connected with the bottom portions of the frame.

3. In a cultivator, the combination of a main frame embodying continuous transverse top bars, spaced front and rear bottom transverse bars arranged in pairs, braces connecting the front and rear transverse bars, front and rear arches connecting the inner ends of the bottom transverse bars with the central portions of the top transverse bars, and bars connecting the outer portions of the bottom transverse bars with the inner portions of the top transverse bars, and cultivating devices carried by the frame and connected with the bottom bars thereof.

4. In a cultivator, the combination of a main frame, cultivating devices mounted on the main frame, handles extending from the said frame, and caster wheels located at the opposite sides of and supporting the main frame and forming a fulcrum for the same to permit the main frame to be tilted backwardly and forwardly to control the cultivating devices.

5. In a cultivator, the combination of a main frame provided with rearwardly extending handles, cultivating devices mounted on the main frame, and caster wheels located at opposite sides of and supporting the main frame and forming a fulcrum for the same to permit the main frame to be tilted backwardly and forwardly to control the cultivating devices, said caster wheels being also pivotally connected at the front of the main frame to permit the same to be shifted laterally.

6. In a cultivator, the combination of a main frame, cultivating devices mounted on the main frame, laterally shiftable frames located at opposite sides of and connected with the main frame, caster wheels mounted on the laterally shiftable frames, and means carried by the laterally shiftable frames for supporting and fulcrumming the main frame, the latter being tiltable backwardly and forwardly to control the cultivating devices.

7. In a cultivator, the combination of a main frame provided at opposite sides with curved tracks, laterally shiftable frames pivotally mounted on the main frame and provided with supporting means receiving the said tracks, and caster wheels mounted on the laterally shiftable frames.

8. In a cultivator, the combination of a main frame, laterally shiftable frames pivotally connected with the main frame, anti-friction wheels mounted on the laterally

shiftable frames in rear of the pivotal points, tracks secured to the main frame and supported by the anti-friction wheels, and caster wheels mounted in the laterally shiftable frames.

9. In a cultivator, the combination of a main frame, a vertically movable rod mounted on the main frame, a caster wheel connected with the rod, and an operating lever 10 fulcrumed on the main frame and also connected with the rod.

10. In a cultivator, the combination of a main frame, a vertically movable rod mounted on the main frame, a caster wheel connected with the rod, an operating lever fulcrumed 15 on the main frame and also connected with the rod, and a coiled spring mounted on the rod for cushioning the main frame.

11. In a cultivator, the combination of a main frame, a vertically movable rod mounted 20 on the main frame, a laterally shiftable frame pivotally connected with the main frame by the said rod and provided with means located in rear of the rod for supporting the main frame, a spring interposed between the laterally shiftable frame and the main frame, an operating lever fulcrumed on the main frame and connected with the laterally shiftable frame, and means for securing 25 the lever in its adjustment.

12. In a cultivator, the combination of a main frame having a curved track, a laterally shiftable frame extending longitudinally of the main frame and provided with an anti-friction device supporting the track, a caster wheel mounted in the laterally shiftable frame and located beneath the anti-friction device, a rod connecting the laterally shiftable frame with the main frame, and a lever 35 mounted on the main frame and connected with the laterally shiftable frame for adjusting the former.

13. In a cultivator, the combination of a main frame, a laterally shiftable frame located 40 beneath and extending longitudinally of the main frame, a caster wheel mounted in the laterally shiftable frame, means carried by the laterally shiftable frame for supporting the main frame, a rod mounted on the main frame and forming a pivot for the laterally shiftable frame, a lever fulcrumed on the main frame and provided at its front portion with an opening receiving the said rod, means for connecting the front end of the lever 45 with the laterally shiftable frame, and means for holding the rear arm of the lever for securing the latter in its adjustment.

14. In a cultivator, the combination of a main frame, wheels supporting the main 50 frame and forming a fulcrum for the same, handles secured at their front ends to the main frame and extending rearwardly therefrom and adapted to tilt the frame on the said wheels, and angle plates or brackets 55 mounted on the main frame and having

means for adjustably supporting the handles, whereby the latter are rigidly connected with the main frame and are adapted to be raised and lowered.

15. In a cultivator, the combination of a main frame, cultivating devices connected therewith, caster wheel frames provided with 70 caster wheels and located at opposite sides of and supporting the main frame, and a removable supporting bar or bolster interposed between the caster wheel frames and the main frame for holding the cultivating devices above the ground.

16. In a cultivator, the combination of a main frame, cultivating devices connected 80 therewith, caster wheel frames provided with caster wheels and located at opposite sides of and supporting the main frame, and a supporting bar or bolster interposed between the 85 caster wheel frames and the main frame and interlocked with the same for rigidly connecting the said frames, said bar or bolster also serving to support the cultivating devices in an elevated position above the ground.

17. In a cultivator, the combination of a main frame, laterally shiftable frames located at opposite sides of and pivotally connected with the main frame, cultivating devices carried by the main frame, a transverse 90 bar or bolster provided at its ends with upwardly and downwardly extending portions interlocked with the main frame and the laterally shiftable frames, and means for securing the bar or bolster in its interlocked relation with the main frame.

18. In a cultivator, the combination of a main frame provided at the bottom with perforations, laterally shiftable frames supporting the main frame, a supporting bar or 105 bolster interposed between the said frames and provided with upwardly extending arms having projecting pins for engaging the perforations of the main frame and provided with lugs also engaging the main frame, and 110 means for securing the bar or bolster in place.

19. In a cultivator, the combination of a main frame provided at the bottom with perforations, laterally shiftable frames supporting the main frame, a supporting bar or bolster 115 interposed between the said frames and having depending arms or portions having recesses to receive the laterally shiftable frames, said bar or bolster being interlocked with the main frame, and means for securing 120 the bar or bolster in engagement with the main and shiftable frames.

In testimony, that I claim the foregoing as my own, I have hereto affixed my signature in the presence of two witnesses.

JOHN HAGEDORN.
